MULTIPURPOSE BATH APPARATUS

Manuel Munar Ocaña, Madrid, Spain, assignor
to Sociedad Anonima de Aplicaciones Sanita-
rias, Madrid, Spain, a Spanish company

Application March 7, 1950, Serial No. 148,027
In Spain April 26, 1949

10 Claims. (Cl. 4—4)

1

This invention relates to a multi-purpose bath apparatus. Disregarding the toilet-bowl, which is not considered bath apparatus and should preferably be placed in a separate room, the modern bathroom comprises at least a bath-tub, wash-stand and bidet. In some installations there are also included a shower-bath, foot-bath and sometimes a child's bath-tub, as well as a chair or stool.

It will be seen that a bathroom comprises a group of equipment occupying a space which is not suited to the characteristics of modern apartments, and that it also requires expensive installations and a network of piping which gives considerable trouble and leakage when embedded in walls or floors. More importantly, such bathrooms represent an enormous waste of water and fuel, both of which it is increasingly important to avoid. The cost of maintenance is also high. My invention avoids these disadvantages. I have evolved a total and perfect synthesis of a modern bathroom, concentrated in less than half the floor space occupied by a normal bath-tub. In this space I have placed multi-purpose bath apparatus performing all the functions of bath-tub, wash-stand, bidet, foot-bath, shower and baby's bath. My arrangement is a bath apparatus economical of area, water, time and fuel, as well as having considerable advantages in hygiene and comfort.

In the drawings:

Figure 1 is a perspective view of a preferred embodiment of my bath apparatus installed in a bathroom, with the near wall of the bathroom removed;

Figure 2 is a plan view of the bath receptacles of Fig. 1;

Figure 3 is a view of the receptacles of Fig. 1, taken in vertical section on the line 3—3 of Fig. 1, looking toward the front;

Figure 4 is a view of the receptacles taken in vertical section at right angles to Fig. 3, on the line 4—4 of Fig. 2, showing the water levels in the inner and outer receptacles;

Figure 5 is a view in detail of the rear end of the outer receptacle showing the foot support;

Figure 6 is a showing of the piping of the installation of Fig. 1, showing the bath receptacles in phantom;

Figure 7 is a view in elevation of the mixer valve and distributor valve;

Figure 8 is a vertical view in side elevation of the pivoted shower arm;

Figures 9 and 10 are views in elevation of the jet shower-head, Fig. 9 showing it adjusted for

2

spraying, and Fig. 10 showing it adjusted for a jet;

Figure 11 is a vertical view in side elevation of the foot valve controlling the water supply for the shower arm;

Figure 12 is a perspective view of the cavity in which the foot valve of Fig. 11 is located;

Figure 13 is a view of my bath apparatus in front elevation, showing the shower-head, curtain and receptacle adjusted for washing the face and hands;

Figure 14 is a perspective view of the apparatus arranged as in Fig. 13, showing a person washing his face and hands, while

15 Figure 15 is a view in front elevation, on a larger scale than Fig. 13, of the front plate and end of the outer receptacle.

The largest single element in the multi-purpose bath apparatus shown in the drawings is an externally rectangular bath receptacle. Inside this outer receptacle is a smaller one B which acts as a bidet. The bidet is centrally located at the head end of the rectangular receptacle. It is conoidal in inner shape and generally oblong in form, with its longest dimension running in a direction from the head end towards the foot of the main receptacle. The upper edge of the head end is formed into a pair of horizontal surfaces A, A which extend between the inner edges of the main bath receptacle and the 20 side edges of the bidet B, overlying the latter slightly. Thus the two surfaces are spaced apart over the bidet. Together, this pair of surfaces form a seat perfectly adapted to the human anatomy, the user being able to sit facing either 25 inwards or outwards. This seat is sloped slightly downward in the direction of the foot end of the main bath receptacle.

In order to prevent any "cross connection" between clean and dirty water when using my 30 bath apparatus, I provide outlet ducts A₁, A₁ extending from the inside of the main receptacle to the exterior of the head end at the outer side edges of the surfaces A, A. As shown in Fig. 4, these ducts A₁, A₁ are at such an elevation 35 as to prevent the level of the water in the main receptacle rising to the level of the water in the bidet. Any overflow through these ducts goes into a curb channel G at the floor level at the end of the main receptacle and thence through 40 a grating G₁ to a waste pipe (not shown).

The bidet B is provided with a water supply nozzle B, connected to a pipe B₂, the nozzle terminating above the level of the water in the bidet but below the level of the seat. The bidet 45 also has a discharge opening B₄ at the bottom.

It will be noted that the edges of the plane surfaces A extend slightly inward beyond the side edges of the bidet, thereby forming anti-splash edges B₅ for the bidet.

The main receptacle of my apparatus is divided vertically into two parts. The lower part is a cavity C of adequate dimensions, first to avoid slipping of the feet as sometimes occurs in other installations, and secondly to enable control of the water supply when taking a medical foot-bath. This lower cavity C has the usual outlet and drain valve P.

The upper part of the main receptacle is formed into horizontal surfaces D at the level where it joins the lower cavity. These plane surfaces D extend along the two sides of the main receptacle and are adapted for use as a seat for children while bathing. In this way children are able to play and get used to water from their youngest days. The shape of the foot end of my main receptacle is one of the novel features of my invention. This end is divided into halves by a vertical cavity F and is formed into foot rests on each side of the cavity suitable for use when taking a foot-shower, jet bath, etc.

Each half of the foot of the receptacle presents a shape comprising an upper portion E inclined downwardly toward the center of the receptacle. This portion E connects with a curve at its lower end forming a cavity E₁ and a plane surface E₂ corresponding to the aforementioned seats D (see Figs. 4 and 5), but preferably inclined slightly downwardly towards the center of the receptacle. It will be seen from Fig. 5 that the shape of the halves therefore follows the anatomic shape of the human foot perfectly, enabling the user to lean his feet comfortably on the slopes when applying soap, or simply to have a rest for them during other hygienic applications with the apparatus.

I also find it preferable to provide a slightly raised edge A₂ around the periphery of the receptacle to receive the lining material of the room or chamber in which the bath apparatus is installed and thereby avoid humidity or leakage (see Figs. 1 and 4).

Turning now to the arrangements for water supply, reference is made more particularly to Figs. 1, 6 and 7. I provide a mixer valve M connected to a distributor valve M₁. The mixer valve M is connected to the cold water supply pipe R and hot water supply pipe T and has an operating lever S which enables the delivery of hot, cold or tepid water to the distributor valve M₁. This latter valve has four outlets. The outlet L₄ leads to a jet shower, the outlet N to a perineal douche set N₁, N₂. The outlet B₂ is the pipe going to the bidet nozzle B₃, and the fourth and final outlet V is another connection to the jet shower through an automatic foot valve shown in Figs. 6 and 11. This valve is for use when the jet shower is used to wash the hands and face, as explained below. The distributor valve M₁ has the usual handle S for connecting the water from the mixer valve to whichever of these four outlets it is desired to connect.

The front wall or head end of my bath apparatus is enclosed by a plate I (see Fig. 15). This plate is mounted on supports K (see Fig. 1) by means of screws J so that the plate can be removed and replaced as necessary.

Medical science considers immersion in bathtubs non-hygienic, but my apparatus operates on the opposite principle. Thus in my apparatus, sprinkling, squirting and spraying of running

water and jets of water at convenient temperature and pressure are used as the only reasonable and scientific method for cleaning the human body because they carry away from the body from head to foot all the dirt, exudations and humors and at the same time strengthen and serve as a tonic for the body.

For these operations attention is called to the articulated and pivoted jet shower (see Figs. 1, 6 and 14). There is a shower pipe or arm L to carry the water to the shower head. The wall end of this shower arm turns on a plate L₁ on the wall, thereby describing a semi-circular trajectory. The arm can lie in any desired position in this semi-circle. At its free end this articulated arm has a turning pivot plate L₂ and fastened on that plate is the head or jet shower L₃ shown in detail in Figs. 9 and 10. This jet shower head is able to make a complete circle of movement about its pivot point on the shower pipe L and can be fixed at any desired angle in this circle. The periphery of the discharge end of the head is knurled and by rotation of this head end the discharge can be changed from the shower or spray of Fig. 9 to the central jet discharge of Fig. 10.

It will be obvious that the apparatus already described can be mounted on or formed from various other types of conduits and valves.

It will be seen that the equipment so far described provides a substitute for a full-length bath-tub.

All the services obtained from the bath equipment of a modern bathroom having running water are replaced to advantage by my simple and novel apparatus. I will now describe the additional equipment necessary to enable my apparatus to be used as a substitute for a wash-stand. I provide a water-proof curtain X shown in Figs. 13 and 14 which is strung by means of rings on a bar Q extending across the head end of the receptacle slightly above waist level. While I have shown the curtain arranged at this level when not using the equipment as a wash-stand, the curtain is normally suspended by means of its bar Q on upper supports O. These upper supports provide a full-length shower curtain. When used as a substitute for a wash-stand the bar is placed on the lower supports O' at waist level, as already mentioned. When properly hung on the lower supports O', the curtain forms an apron preserving the body from splashing water. When the user is ready to wash his face and hands or his arms and entire head, the arm L₁ is lowered and the jet shower L₃ turned upward to the position shown in Figs. 13 and 14, thus providing an ascending water jet or shower. In the plate I at the head end of the receptacle at the floor level are two openings H, H₁ into which the bather puts his feet. This enables him to get close to the curtain and the jet shower and have the body in a perfectly comfortable position while washing. The water is mixed to the desired temperature by means of the water mixer valve M. Then the lever S of the distributor valve M₁ is turned so as to establish communication between the distributor valve M₁ and a button V₁ of a valve V in the cavity H₁. When the bather presses on this button with his foot, the water spray or jet from the articulated shower pipe L and jet shower head L₃ provides the necessary water.

Another use of my bath apparatus is in substitution for the usual bidet. When the parts 75 are arranged as described, the receptacle B is

part of a perfect form of bidet system. Water is supplied through the nozzle B_3 and the bidet can be drained, when necessary, through the outlet B_4 . The overflow edge B_1 and the anti-splash edges B_5 of the seat control the water in an ideal manner.

The arrangement of the bidet between the two plane surfaces A , A allows the bather to sit comfortably upon the said surfaces, facing either inwards or outwards, as if on a chair. This obviously is more comfortable than the ordinary bidet where the user is obliged to "ride" upon a narrow and uncomfortable edge.

A perineal douche can also be obtained with the stationary water in the bidet B or with a flowing supply of water if the nozzle B_3 is left open. When this nozzle is open, of course, the water will flow away constantly over the edge B_1 of the bidet. It should be noted that in some countries the ordinary bidet installation is not permitted because of the design not completely preventing the contamination of fresh water supply with dirty water. This contamination occurs through openings on the inner and upper walls of ordinary bidets when a stoppage and back siphon are produced by obstructions in the drainage conduits. My novel bidet construction avoids any possibility of such cross connection and contamination owing to the fact that any dirt or water in the bidet B never can reach the level of the fresh water nozzle B_3 . Instead, the waters in the bidet flow over the edge B_1 and fall into the main bath receptacle, from whence they flow through the outlet ducts A_1 .

If desired, the bidet service can be rounded out by installation of a portable perineal douche N_1 , N_2 (see Fig. 1).

My novel bath apparatus also represents the perfect and comfortable solution for foot-baths heretofore known.

In order to take a foot-bath the bather sits on the plane surfaces A , A , turns the articulated jet shower down and opens the jet until the cavity C of the main receptacle is filled to a convenient level. When it is desired to wash the feet by means of a jet or shower, the same manipulation is used, but the jet or shower is directed at the feet of the user which alternately are leaned against the slopes E_1 , E_2 at the foot end of the main receptacle.

As already mentioned, my apparatus serves equally well for bathing children, who can sit on the plane surfaces D at the upper edge of the lower cavity C while the shower arm L and the jet shower L_2 are manipulated as desired.

Reference is made to my co-pending application Serial No. 32,109, filed June 10, 1948 (now Patent No. 2,589,280), containing claims directed broadly to the seat shown in the present application without reference to any perineal shower cavity or bidet. Reference is also made to my co-pending application Serial No. 109,333, filed August 9, 1949 (now Patent No. 2,589,281), which contains claims to the seat shown in the present application in connection with a perineal shower cavity.

I claim:

1. Multi-purpose bath apparatus comprising a rectangular bath receptacle having an entirely planar bottom and a seat at the front end of the receptacle, in combination with a small, oblong bidet whose body is almost entirely outside the receptacle and located midway of the upper front of the receptacle, the entire edge of said bidet except a small front sector which projects over the

receptacle being covered by the lower face of the seat following the contours of an opening formed in the center of the seat to permit the use of the bidet but leaving a small flange or anti-splash edge; and a separate water supply means and waste connection for the bidet independent of the receptacle.

2. Multi-purpose bath apparatus comprising an externally rectangular bath receptacle and a receptacle mounted mid-way of the head end of the rectangular receptacle and inside same, in combination with two plane surfaces provided at the head end of the outer receptacle covering the space between external edges of both the outer and inner receptacles, said two plane surfaces being spaced apart over said inner receptacle and together forming a seat adapted to the human anatomy.

3. Multi-purpose bath apparatus according to claim 2 in which in the outer receptacle, laterally outside said plane surfaces, are outlet ducts forming an overflow system for the outer receptacle below the upper edge of the inner receptacle, whereby any mixing of the water in the outer receptacle with the water in the inner receptacle is prevented.

4. Multi-purpose bath apparatus according to claim 1 wherein at one end of the outer receptacle are two outlet ducts forming an overflow for the water in the outer receptacle, whereby any mixing of the water in the outer receptacle with that in the inner receptacle is prevented.

5. Multi-purpose bath apparatus according to claim 1 wherein the inner face of the foot end of the outer receptacle is divided into halves by a vertical cavity, said halves being inclined inwardly toward the bottom, whereby the user's feet can be rested against them when the user is seated at the head end of the outer receptacle.

6. Multi-purpose bath apparatus according to claim 5, wherein each of the foot halves has an upper part inclined inwardly toward the bottom of the receptacle, said upper incline merging at its lower end into a cavity ending in a horizontal surface slightly inclined inwardly toward the bottom of the receptacle, this shape following the anatomic shape of the foot, whereby the user can lean his feet comfortably on the foot halves when applying soap, or simply have a rest for his feet while using the bath apparatus.

7. Multi-purpose bath apparatus according to claim 1 in which there are a pivoted jet shower above the receptacles, a foot valve for said shower employed when the shower is to be used for washing face, head or hands, in combination with a perineal douche, a water mixer and a distributor connecting the water to the jet shower, the perineal douche, the bidet, the water supply or the foot valve, as desired.

8. Multi-purpose bath apparatus according to claim 1 in which there are a pivoted jet shower above the receptacles and a foot valve therefor employed when the shower is used to wash the face, head or hands, said shower comprising a pipe arm and a pivot plate rigidly supported on a wall of the room in which the bath apparatus is installed, said pipe arm being connected to the plate and adapted to be moved by hand to any desired position in a vertical, semi-circular trajectory, in combination with a turning pivot plate on the other end of the pipe arm and a jet shower head attached to the said pivot plate adapted to turn up or down, said jet shower head

7
being adapted to produce either a jet or a spray, as desired.

9. Multi-purpose bath apparatus according to claim 1 in which there are a pivoted jet shower above the receptacles and two cavities located in the lower front wall of the outer receptacle in which the user can put his feet in order to maintain a comfortable position when using the shower to wash the face, head or hands, and a valve in the bottom of one of said cavities connected to said jet shower, whereby pressure of the foot will produce a water spray or jet from the jet shower.

10. Multi-purpose bath apparatus according to claim 1 in which there is front wall on the outer receptacle in combination with a movable

5
plate covering the front wall and screws fastening said plate in position.
